DESIGN FOR A BADGE

Theodore J. Dworzynski, Washington, Ind.

Application February 15, 1943, Serial No. 109,547

Term of patent 7 years

To all whom it may concern:

Be it known that I, Theodore J. Dworzynski, a citizen of the United States, residing at Washington, in the county of Daviess and State of Indiana, have invented a new, original, and ornamental Design for a Badge, of which the following is a specification, reference being had to the accompanying drawing, forming part thereof.

I claim:

The ornamental design for a badge, as shown.

THEODORE J. DWORZYNISKI.
